METHOD AND APPARATUS FOR CLEANING
METAL STRIP

John F. Ferm and Edward William Hopper, Midland, Pa., assignors to Pittsburgh Crucible Steel Company, Pittsburgh, Pa., a corporation of Pennsylvania

Application August 10, 1938, Serial No. 224,100

2 Claims. (Cl. 202—169)

This invention relates to method and apparatus for cleaning strip metal, such as tin-coated steel strip.

In any process of tin-coating strip steel, the strip must be cleaned at various stages of the procedure. Of particular importance is the final cleaning of the coated strip following the treatment which imparts a bright, mirror-like finish thereto. This mirror finish may be applied, for example, to the matte coating obtained by electrodeposition, by passing the strip first through a hot oil bath of appropriate temperature and characteristics, such as palm oil, and thence through a cool oil bath, the former to fuse the coating to a bright surface and the latter to harden the coating so brightened.

On emerging from the latter bath the excess oil adhering to the strip may be removed mechanically, by passing the strip between a pair of rolls of rubber or the like rotating under compression, so-called squeegee rolls. Other agencies must be employed thereafter to remove the residual oil and other surface contaminations. Attempts to remove these contaminations by means of a cleansing spray or by a condensation of vapor on the strip, have proved unsatisfactory or ineffective. Also the known arrangements for cleaning by immersion in liquid solvents are unsatisfactory.

Heretofore the latter practice has been carried out by merely feeding the strip progressively through several separate tanks of a cleaner liquid, such as carbon tetrachloride. With this procedure the cleaner liquid in the tank first encountered by the strip soon becomes so contaminated with the oil, etc., that cleaning action in this tank practically ceases, in consequence of which the second tank of the series is then quickly rendered equally contaminated, and so on for each succeeding tank until the strip undergoes substantially no cleaning in passing through all of the tanks. The system, therefore, cleans effectively only for a short time after the tanks have been freshly filled with cleaner liquid, the cleaning action decreasing progressively thereafter until the tanks are refilled. As a result the cleaned strip is not of uniform quality but varies from time to time in cleanliness and appearance in accordance with the condition of the baths.

The present invention overcomes the above noted and other defects by a novel construction and arrangement of cleaning baths employing a solvent liquid, and by a novel method of operating the same. According to the invention the strip to be cleaned is fed progressively through a

succession of baths containing a cleaning liquid, and a flow of the liquid established in the opposite direction between the baths, the baths being suitably interconnected for this purpose and cleaning liquid withdrawn, preferably continuously, from the first bath traversed by the strip, and, after purification, returned to the tank last traversed by the strip.

In this way the first bath traversed by the strip removes most of the oil, etc. from the strip, and hence becomes most contaminated, the strip thereafter traversing progressively cleaner baths as the strip itself becomes progressively cleaner. The system is, therefore, highly efficient both as to the required additions of purified cleaner and as to the uniformly high degree of cleanliness imparted to the strip.

After the strip has been cleaned in the manner aforesaid it is passed between squeegee rolls for mechanically removing as much of the cleaning liquid adhering thereto as possible, following which it is passed through an evaporator of novel construction in accordance with a feature of the invention, for drying the strip.

In the drawing:

Fig. 1 shows schematically a preferred modification of a strip metal cleaning system in accordance with the invention; while

Fig. 2 is a section at 2—2 of Fig. 1 showing the above mentioned novel details of the evaporator.

Referring to the drawing, there are shown four cleaning baths 1 to 4 inclusive, arranged in succession and contained in tanks 5, 6, provided with partitions 8, 9 respectively for separating the baths 1, 2 and 3, 4 respectively. The metal strip 10 to be cleaned, such as brightened, tin-coated strip steel, is passed between squeegee rolls 11 and thence into bath 1 and under a roll 12 immersed therein. The strip then passes from bath 1 between a pair of felt members 13 or the like disposed in an orifice of partition 8; thence into bath 2 and under roll 14 therein; thence out of bath 2 over roll 15 and into bath 3 and under roll 16 immersed therein; thence out of bath 3 between a pair of felt or like members 17 disposed in an orifice of partition 9, and into bath 4 and under roll 18 immersed therein; thence out of bath 4 between a pair of squeegee rolls 19 of rubber or the like; and thence through an evaporator 20, passing out of the system over a roll 21.

Pure cleaning liquid is fed into bath 4, preferably continuously, at a properly adjusted rate, through an inlet pipe 22. The liquid of bath 4 in turn flows or seeps at about the same rate

through and around the felt members 17 in partition 8, into bath 3. The liquid in this bath in turn flows correspondingly into bath 2 over the low barrier separating tanks 5 and 6. Also the liquid of bath 2 flows correspondingly into bath 1 through and around the felt members 13 in partition 8. The liquid of bath 1 is in turn drawn up at a corresponding rate by an intake line 24 and passed into a purifier and oil separator 25, such as an oil still, the purified cleaner liquid being returned over pipe line 26 to a reservoir 27 from which the outlet pipe 22 is fed through a control valve 28. The oil separated from the cleaner liquid in purifier 25 is returned over a pipe line 28 to hot oil bath (not shown) through which the metal strip 10 passes as aforesaid prior to cleaning. In this way a positive flow of the liquid is established between the baths in the direction opposite to that in which the metal strip 10 is fed.

As cleaning liquid for the baths, such solvents may be used as carbon tetrachloride, trichlor-ethylene, perchlor-ethylene, cleaner's naphtha, etc. The first of these solvents is preferred owing to its fireproof properties and its low vapor pressure at atmospheric temperature.

In the operation of the system, bath 1 removes most of the oil and other impurities from the wholly uncleared strip entering the same. This bath is, therefore, the most contaminated because of this and because it receives the flow and the impurities therein from all of the other baths. Each of baths 2, 3 and 4 is in turn progressively cleaner than that preceding, because the strip is cleaner as it enters and because the liquid which flows into it comes from a cleaner source, namely, from the preceding bath in the direction of flow, except for bath 4 which, however, is fed the highly purified cleaner of reservoir 27. As the strip traverses the bath it, therefore, becomes progressively cleaner and traverses progressively cleaner baths until on entering, in a well cleaned condition, bath 4 of high purity, all residual traces of oil, etc. are removed.

The vapor level above the baths is kept low by means of the pipes 30 disposed above the baths and within which cold water is circulated.

As the strip passes out of bath 4, the greater portion of the solvent adhering thereto is mechanically removed by passage through the squeegee rolls 19. The solvent remaining on the strip is thereupon removed by evaporation as the strip passes between the plates 31, 32 heated by steam pipes 33, 34, forming part of the evaporator. Referring to Fig. 2, the solvent thus vaporized flows off laterally to the left and right between a series of cold water pipes 35, 36, which

condense the vaporized solvent to the liquid state again out of contact with the strip.

To facilitate examination of the apparatus and the strip, the cover for the baths is made up of a series of removable plates 37; while the rollers 5 12, 14, 16, 18, are mounted on pivoted arms 38 affixed to levers whereby the rolls may be swung up to the position indicated by the dotted line 39.

What we claim is:

1. Apparatus for cleaning surface contaminated metal strip, which comprises: a plurality of baths containing cleaning liquid and disposed in sequence, feed-roll conveying means for feeding said strip longitudinally in one direction through said baths successively, means for establishing a flow of said liquid between said baths successively and in the direction opposite to that in which the strip is fed, means for cascading said flow between at least some of said baths, means for removing a portion of the highly contaminated liquid in the first bath of said sequence traversed by said strip, means for purifying the liquid so removed and for returning the purified liquid to the final bath of said sequence traversed by said strip, means for mechanically removing a portion of the cleaning liquid adhering to said strip upon emergence from said baths, means for evaporating to dryness the residual liquid retained on said strip, and means for condensing the evaporated liquid out of contact with said strip.

2. Apparatus for cleaning surface contaminated metal strip, which comprises: a plurality of baths containing cleaning liquid and disposed in sequence, feed-roll conveying means for feeding said strip longitudinally in one direction through said baths successively, means for establishing a flow of said liquid between said baths successively and in the direction opposite to that in which the strip is fed, means for cascading said flow between at least some of said baths, means for removing a portion of the highly contaminated liquid in the first bath of said sequence traversed by said strip, means for purifying the liquid so removed and for returning the purified liquid to the final bath of said sequence traversed by said strip, means for mechanically removing a portion of the cleaning liquid adhering to said strip upon emergence from said baths, means including a pair of heated plates between which the strip is passed, for evaporating to dryness the residual liquid retained on said strip, and condensing means laterally disposed with respect to said heated plates, for condensing the evaporated liquid out of contact with said strip.
